UNITED STATES PATENT OFFICE.

CLEMENT MOSES HAHN, OF VALENTINE, NEBRASKA.

IDENTIFICATION-TAG.

1,314,745.

Specification of Letters Patent. Patented Sept. 2, 1919.

Application filed April 2, 1918. Serial No. 226,193.

To all whom it may concern:

Be it known that I, CLEMENT MOSES HAHN, a citizen of the United States, and a resident of Valentine, in the county of 5 Cherry and State of Nebraska, have invented certain new and useful Improvements in Identification-Tags, of which the following is a specification.

My invention is an improvement in identification tags, and has for its object to provide a tag of the character specified, especially adapted for identifying motor vehicles, wherein the tag, preferably of shield shape, and of metal, is provided with an annular field for receiving embossed numerals, there being sufficient space for ten numerals, and the tags being identified by the numerals, the tag being adapted for connection with a motor vehicle over an opening provided in the vehicle, the tag closing the opening and being secured to the vehicle, and clearly advertising by the opening left by the removal of the tag that the tag has been removed.

25 In the drawings:

Figure 1 is a front view of the improved tag;

Fig. 2 is a transverse section through the tag and the portion of the vehicle to which it 30 is connected.

The present embodiment of the invention is shown in connection with a portion 1 of a motor vehicle, the said portion having an opening 2 over which the tag 3 is secured, and this opening preferably is a five pointed star, although it is obvious that it may be of any desired contour, but it is of such size that the tag may be secured to the vehicle over the opening to conceal the opening. The 40 tag 3 in the present instance is of shield shape and has at its top 2 and at its bottom

1 openings which are adapted to receive star headed bolts 4 for securing the shield to the vehicle.

The shield 3 which is of any suitable metal 45 has an annular field 5 which is formed by embossing rings 6 and 7. Within this field are arranged numerals 8, the said numerals being embossed at approximately the same height as the rings, and these numerals identify the shield and the vehicle to which it is attached, as, for instance, the first shield issued would bear the numeral 1, the second, the numeral 2, and in such manner the space provided in the field permits the issue of 55 1,235,567,890 shields.

The shield is of such size that it would cover and conceal the opening 2, and it will be obvious that should the shield be removed to prevent identification, the opening 2 would be a plain advertisement that such shield had been removed and would call attention and suspicion to the vehicle. These shields may bear any other identifying matter or the like that may be thought 65 desirable or advisable.

I claim:

In combination with a motor vehicle having an opening, of an identification plate arranged over the opening and covering and 70 concealing the same and adapted to display the opening when the plate is removed to call attention to the removal of the plate, said plate and vehicle having registering openings around the first named opening 75 and spaced apart therefrom, bolts engaging the openings, and nuts engaging the bolts on the opposite side from the plate.

CLEMENT MOSES HAHN.
